PYROPHORIC LIGHTING MECHANISM

Louis V. Aronson, Newark, N. J., assignor to Art Metal Works, Inc., a corporation of New Jersey

Original application March 29, 1935, Serial No. 13,627. Divided and this application October 26, 1936, Serial No. 107,547

5 Claims. (Cl. 67—4.1)

My invention relates to pyrophoric lighting mechanism of the type comprising a torch utilizable for purposes such, for example, as the ignition of cigars, cigarettes, pipes, etc.

5 My invention, in an important phase thereof, relates to pyrophoric lighting mechanism constructed and arranged in such manner that a detachable torch arrangement may be utilized as a lever to actuate the sparking device of said 10 mechanism.

Various other objects, advantages and characteristics of my invention will become apparent from the following detailed description.

15 My invention resides in the pyrophoric lighting mechanism, combinations and features of the character hereinafter described and claimed.

This application is a division of my application Serial No. 13,627, filed March 29, 1935.

For an understanding of my invention and for 20 an illustration of one of the many forms thereof, reference is to be had to the accompanying drawing, in which:

25 Figure 1 is a vertical sectional view, partly in section, of pyrophoric lighting mechanism as constructed in accordance with my invention;

Fig. 2 is a vertical sectional view, partly in elevation, corresponding generally with Fig. 1 but showing a different relation of some of the parts;

30 Fig. 3 is a horizontal sectional view, partly in plan, and is taken on the line 3—3 of Fig. 2 looking in the direction of the arrows;

Fig. 4 is a fragmentary, transverse vertical sectional view, partly in elevation, of the spark-producing unit;

35 Fig. 5 is a vertical sectional view, partly in elevation, of a torch arrangement; and

Fig. 6 is a horizontal sectional view, partly in plan, and is taken on the line 6—6 of Fig. 5 40 looking in the direction of the arrows.

As disclosed on the drawing, there is shown a main casing C which is formed from sheet metal or other suitable material and which may be open at the bottom thereof so that a fuel 45 casing F may be telescopically received therein in freely detachable relation. Suitably secured to the main casing C is a cover plate P which has a pair of spaced, depending lugs 1, 1a soldered or otherwise suitably fastened thereto. Suitably 50 secured to these lugs, as by screws 2 is a depending frame 3 which forms a support for the hereinafter described operating mechanism, said frame, for example, being of generally rectangular configuration as shown in Fig. 3.

55 Disposed within the shell formed by the frame

3 is a member 4 which extends in generally a vertical direction, the upper end 4a of said member 4 extending through an opening 5 formed in the cover plate P. As shown in Figs. 1 and 2, the upper end 4a of said member 4 is provided with a depression 4b, the latter being utilizable as hereinafter described. The member 4 is intended to oscillate in a vertical plane disposed longitudinally of the main casing C and, to this end, the lower end of said member 4 may be provided 5 with a pin 4c which seats loosely within an opening formed in the bottom wall of the frame 3. As illustrated on the drawing, the member 4 is biased, for example, by a leaf spring 6 in a clockwise direction, Figs. 1 and 2, said leaf spring 6 15 being conveniently secured to said lower wall of the frame 3. The member 4 further comprises a pin 4d extending laterally thereof and being utilizable as hereinafter described.

A pin 7, horizontally disposed in the side walls 20 of the frame 3, is adapted to support a lever 8, one horizontal arm of which is notched as indicated at 8a for detachable engagement with the aforesaid lateral pin 4d. The other horizontal arm of the lever 8 is connected by a pin-and-slot 25 connection 9 with the shank sections of a collar 10 which is soldered or otherwise suitably secured to a sleeve 11 mounted for vertical, reciprocatory movement in aligned passages formed, respectively, in the bottom wall of the frame 3 and the cover 30 plate P. As shown in Figs. 1 and 2, a helical spring 12 encircles the lower part of the sleeve 11 and is disposed between the lower wall of said frame 3 and the collar 10, said spring 12 constantly biasing the collar 10 and the sleeve 11 35 in an upward direction toward a stop member 13 carried by the side walls of said frame 3.

The aforesaid lever 8 comprises a section 8b extending in generally a vertical direction, said lever section 8b terminating on its upper surface 40 in a set of rack teeth 8c. These rack teeth 8c are adapted to mesh with a pinion 14 of a pyrophoric spark-producing unit from which sparks are projected along a path extending above the upper end 4a of the member 4, said pinion 14 45 being freely rotatable on a pin or axle 15 supported horizontally in a standard 16 upstanding from the cover plate P. Formed integrally with the pinion 14 is a sleeve 17, the pinion and sleeve being freely rotatable on the axle 15. Freely 50 rotatable on the sleeve 17 is a wheel 18 having a serrated or roughened outer peripheral face. The side of the serrated wheel 18 removed from the pinion 14 is provided with rack teeth 18a 55 with which coacts a ratchet disk 19 mounted on

the adjacent end of the sleeve 17, said ratchet disk 19 being biased from right to left, Fig. 4, by a coiled spring 20 which is disposed between said disk 19 and a nut 21 threaded to the outer 5 end of the axle 15. The ratchet disk 19 is freely slidable axially of the projecting end of the sleeve 17 but is otherwise fixed thereto so as to be rotatable therewith. As shown in Figs. 1 and 2, the above described spark-producing unit is enclosed 10 by a cap structure 22 suitably secured to the cover plate P and provided with an opening 22a through which the pyrophoric sparks are adapted to pass along the above noted path. As illustrated, the cap structure 22 defines a surface 15 22b forming a fulcrum to be engaged, in the manner hereinafter described, by the torch member.

The torch member utilizable with the form of my invention herein shown may be of any suitable character as well known in the art. Or, if desired and as shown in Figs. 5 and 6, said torch member may comprise a tubular member 23 terminating in an upper handle section 23a, the lower surface of which defines a flanged surface 23b, 25 Fig. 1. Adapted for association with the member 23 is a member 24 which comprises a shank 24a adapted to be detachably received in the tubular opening at the bottom of said member 23. As shown, the member 24 is of flat configuration 30 and is so shaped as to define a tapered lower section 24b. A wick 25 folded into flat U-configuration axially of the member 24 is secured thereto in any suitable manner, as by the flexible wire 26 which is seated in slots 24c formed at 35 opposite edges of said member 24.

It will readily be understood that the ends of the wick 25 are exposed below the lower end of the tubular member 23.

Accordingly, when the torch member is associated with the complete mechanism as shown in 40 Fig. 1, it results that the lower ends of the wick 25 come within the vertical passage defined interiorly of the fuel casing F. As a result, fuel is absorbed by the wick 25 and, since the latter is 45 of substantial length, the supply of fuel which may be taken up by said wick is relatively large.

As the parts are shown in Fig. 1, the lever 8 is in its extreme position in a clockwise direction. The spring 12 is under compression and is so 50 maintained by reason of the fact that the pin 4d of the member 4 is engaged by the notched section 8a of the lever 8.

When the mechanism is to be operated, the handle section 23a of the torch member is grasped 55 to manually remove the same from the tubular member 11 and the tapered section 24b at the lower end of the torch member is positioned in the depression 4b at the upper end of the member 4. Then, in suitable manner, as by utilization 60 of the surface 22b of the cap structure 22 as a fulcrum, the member 4 is moved in a counter-clockwise direction, Fig. 1, to disengage the pin 4d from the notched section 8a of the lever 8. As soon as disengagement of these parts is thus 65 effected, the spring 12 is released and expands with a snap action to elevate the collar 10 against the stop surface 13 and to swing the lever 8 in a counter-clockwise direction, Fig. 2. The rack 70 teeth 8c of the lever 8 coat with the pinion 14 and, therefore, a step of movement is imparted to the serrated wheel 18 whereby a shower of pyrophoric sparks are produced, these sparks passing along a path which extends through the opening 22a of the cap structure 22 and igniting the 75

charge of fuel carried by the lower ends of the wick 25.

After the torch member has served its intended ignition purpose, it may again be introduced into the tubular member 11. After the flanged surface 23b thereof engages the upper end of said tubular member, continued downward application of pressure produces downward movement of the tubular member to thereby compress the spring 12 and move the lever 8 from the position shown in Fig. 2 to that shown in Fig. 1. When the lever 8 reaches the position last named, the pin 4d of the member 4 comes into engagement with the notched section 8a of the lever 8 to thereby latch the parts in their respective positions as shown in Fig. 1 so as to be in condition for subsequent automatic operation in the manner hereinbefore described.

It is to be understood that the mechanism hereinbefore specifically described is merely illustrative of the many embodiments which the invention may take. Thus, for example, in lieu of the described spark-producing mechanism, it shall be understood that other equivalent arrangements for obtaining uni-directional movement of a serrated wheel may be utilized. Furthermore, it is to be understood that fuel may be supplied to the fuel casing F in any convenient manner. It shall also be understood that the sealing arrangement interiorly of the fuel casing F for the lower end of the torch member may assume any one of a variety of forms in accordance with the broad purview of the invention.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. A lighter comprising a casing, pyrophoric spark producing means on the top of said casing, spring means for operating said spark producing means to produce a shower of sparks, means within the casing for controlling the energization and release of said spring means and including latching means for said spring means, the latching means also comprising a vertically extending latch control member having its upper end exposed adjacent the path of said sparks, means mounting said member whereby said upper end is tiltable to latching and unlatching positions, and fulcrum means positioned above and adjacent said upper end, said upper end being formed for engagement with, and to be tilted to unlatching position by, a removable torch member when applied in upstanding position to said end and said fulcrum means, said end and said fulcrum being so positioned that the torch member when thus applied will be in said path of sparks.

2. A lighter comprising a casing, pyrophoric spark producing means on the top of said casing, spring means for operating said spark producing means to produce a shower of sparks, means within the casing for controlling the energization and release of said spring means and including latching means for said spring means, the latching means also comprising a control member protruding above said casing at a point adjacent the path of said sparks, means mounting said member whereby its protruding portion is mov-

able in normally substantially horizontal directions into latching and unlatching positions, a removable rod-like torch member and fulcrum means positioned adjacent said portion, said portion being formed to receive and to be moved by said removable torch member when applied in an upstanding position to said portion and said fulcrum means, said portion being so positioned that such torch when thus applied will be within 10 said path of sparks.

3. A lighter comprising a casing, pyrophoric spark producing means on the top of said casing, spring means for operating said spark producing means to produce a shower of sparks, means for 15 energizing said spring means, latching means for said spring means, said latching means comprising a control member protruding above said casing at a point adjacent the path of said sparks, means mounting said member whereby its 20 protruding portion is movable in normally substantially horizontal directions into latching and unlatching positions, and fulcrum means comprising in part a housing means for said spark producing means, said portion being formed to receive and to be moved by a removable torch member when applied to said portion and said fulcrum means.

4. A lighter comprising a casing, pyrophoric spark-producing means mounted on the top 30 thereof, an operating member pivoted within said casing beneath said means, a vertically extending arm on said member operatively associated with said means for actuating the latter, a torch receiving cavity extending into said casing from a 35 point at one side of said spark-producing means,

spring means in the casing adapted to be energized by the insertion of a torch into said cavity, said spring means being operatively associated with said pivoted member to normally bias the same for actuating movement, a second arm on 5 said pivoted member and integral with the first named arm but extending horizontally in a direction opposite said cavity, latching means for said spring means associated with said second arm and including a member protruding from the top 10 of said casing adjacent the path of sparks from said sparking means and adapted to be operated by engagement with a torch member.

5. A lighter comprising a casing, pyrophoric spark-producing means mounted on the top 15 thereof, an operating member pivoted within said casing beneath said means, an upwardly extending portion on said member operatively associated with said means for actuating the latter, a torch receiving cavity extending into said 20 casing from a point at one side of said spark-producing means, spring means in the casing adapted to be energized by the insertion of a torch into said cavity, said spring means being operatively associated with said pivoted member 25 to normally bias the same for actuating movement, another portion on said pivoted member extending in a direction opposite said cavity, latching means for said spring means associated with said last named portion and including a 30 member protruding from the top of said casing adjacent the path of sparks from said sparking means and adapted to be operated by engagement with a torch member.

LOUIS V. ARONSON. 35
